(57) **CLAIM**

I claim the ornamental design for a no bark collar device, as shown and described.

DESCRIPTION

FIG. 1 is a top right perspective view showing a no bark collar device in accordance with the present design;
FIG. 2 is a front elevation view thereof;
FIG. 3 is a rear elevation view thereof;
FIG. 4 is a top plan view thereof;
FIG. 5 is a bottom plan view thereof;
FIG. 6 is a side view thereof; and,
FIG. 7 is an opposite side view thereof.
